UNITED STATES PATENT OFFICE.

HENRY FRANCIS KEIL, OF BRONXVILLE, NEW YORK.

ELECTRIC FLOOR PUSH-BUTTON.

No. 903,577.

Specification of Letters Patent.

Patented Nov. 10, 1908.

Application filed March 8, 1908. Serial No. 419,010.

To all whom it may concern:

Be it known that I, HENRY FRANCIS KEIL, a citizen of the United States of America, and a resident of Bronxville, in the county 5 of Westchester and State of New York, have invented a certain new and useful Electric Floor Push-Button, of which the following is a specification, the same being a full, clear, and exact description of the 10 invention, such as will enable others skilled in the art to which it appertains to make and use the same.

This invention relates to electrical devices, and in particular to a knob or plunger by 15 pushing or pressing which the circuit of an electric bell or other electrical apparatus may be completed, and adapted to be affixed to the floor or other suitable supporting structure, and it has for its object the provision of an article of the class described, 20 simple in construction, inexpensive to manufacture, and which is durable and efficient in practical use.

To attain the desired end the invention 25 consists in the combination, arrangement and operation of parts herein set forth.

In order to enable the invention to be fully 30 understood, I shall proceed to explain the same by reference to the drawings, illustrative of one embodiment of the invention, which accompany and form a part of this specification, and in which

Figure 1 represents a sectional view of a 35 device constructed according to my invention, Fig. 2 is a section taken through the insulating body of the push button, Fig. 3 is a detail of my retaining plate, and Fig. 4 is a side elevation of the device.

Like letters of reference indicate like 40 parts in all the views.

Referring particularly by reference symbols or characters to the drawings, A denotes a face plate constructed and arranged to be secured to the floor, and formed with 45 a central orifice a, and outer orifices a'.

B designates a preferably cylindrical body 50 of insulating material having a central bore b and a lower contracted neck b', and D is a plate constructed and arranged to lie beneath said cylindrical body and formed with threaded apertures d and also ordinarily having recessed portions d².

Screws E, which preferably lie in grooves 55 b² located in the body B serve to hold the plate D and intermediate body B rigidly to the face plate A, whereby the said body B

is not only held firmly in position, but is adapted to resist any strain which it may be caused to bear.

A pin F works in the central orifice or bore a of the device and is ordinarily made with a shoulder on which rests a thimble or sleeve f, which latter, together with the plunger, is held in an elevated normal position by the spring f' working in the bore b, 60 any undue upward movement of the said thimble being prevented by an annular flange formed on the top of the said open thimble which is somewhat larger than the bore a, which flange rests against the lower 65 surface of the face plate A.

Two spring fingers C are ordinarily screwed to the exterior of the cylindrical body B by screws C', which also serve for means of attachment thereto of the wires of 70 the electric circuit.

The ends of the spring fingers C are constructed and arranged to be normally separated by a dielectric medium, as the atmosphere, but to be electrically connected by 80 means of the lower end of the plunger F when it is forced down between the two said spring fingers upon pressing the head of the plunger, which normally stands a little above the surface of the floor.

In operation, the push button is placed in proper position in the floor, and the wires of the electric circuit are fastened to the spring fingers C, and upon pushing the plunger F in a downward direction, and thereby compressing the spring f', an electric connection will be made between the two said spring fingers and the circuit will be thereby closed, and the electro-magnet of the signaling instrument located in the electric circuit 90 will be energized, whereby the desired call will be sounded, and upon releasing the pressure on the plunger, the latter will be restored to its normal elevated position by means of the resilience of the spring by which 95 it is sustained.

I wish it to be understood that I do not desire to be limited to the exact details of construction shown and described, for, obviously, modifications will occur to a person 105 skilled in the art.

What I claim as my invention is:

1. A face plate having a central orifice, a body made of dielectric material having a bore with a contracted neck to register with 110 the said orifice, a spring in said bore adapted to support a thimble, in combination with

said thimble, two converging spring fingers mounted on the insulating body, a shouleder plunger to rest on the thimble and to work in the said contracted neck, a retaining plate located beneath the insulating body, and screws passing through the face plate and secured to the said retaining plate.

2. A face plate, a plunger, two spring fingers, a body made of dielectric material to support the same, a retaining plate located below the insulating body, and screws to fasten together the face plate and the retaining plate.

3. A face plate, two spring fingers, a body made of dielectric material to support the

same; and having a bore and two exterior grooves, a retaining plate located below the insulating body, a plunger to work in the said bore, and screws placed in the said grooves intermediate the face plate and the retaining plate to fasten the two together. 20

In testimony of the foregoing specification I do hereby sign the same in the City of New York, county and State of New York, this 13th day of February 1908.

HENRY FRANCIS KEIL.
